UNITED STATES PATENT OFFICE.

PETER PETERSEN, OF OAKLAND, CALIFORNIA.

BROOM-PROTECTOR.

1,305,157.

Specification of Letters Patent. Patented May 27, 1919.

Application filed September 28, 1918. Serial No. 256,121.

To all whom it may concern:

Be it known that I, PETER PETERSEN, a subject of the King of Norway, residing at Oakland, in the county of Alameda and

5 State of California, have invented certain new and useful Improvements in Broom-Protectors, of which the following is a specification, reference being had to the accompanying drawings.

10 This invention relates to devices for preventing brooms from getting out of shape and holding the broom straws from breakage and deformation.

The general object is to provide a device 15 of this character embodying a loop adapted to be slipped over the broom below the stitching thereof and having thereon means whereby it may be securely clamped in place upon the broom.

20 A further object is to provide a device of this character which is so formed that it may be adjusted to brooms of different sizes.

A further object is to provide a device of 25 this character which may be easily slipped in place upon a broom and then afterward anchored in place thereon.

Other objects will appear in the course of the following description.

My invention is illustrated in the accompanying drawings, wherein:—

Figure 1 is a side elevation of a broom with my protector applied thereto;

Fig. 2 is a perspective view of the protector showing the key used for engaging 35 the member 15 with the protector.

Referring to these drawings, it will be seen that my device comprises an elliptical loop adapted to embrace the straws of the broom, this loop being formed of two wire 40 sections 10 and 11 bent to form semi-ellipses and parallel coacting legs. The section 11 at its ends is bent to provide upwardly extending arms 12 formed with hooks 13 at their ends. The section 10 at its ends is coiled

45 once or twice around the section 11 and formed to provide the upwardly extending arms 12 having hooks 13. These arms 12 are resilient or are resiliently urged toward each other by the coils forming the bases of the

50 arms. It will be seen that the two sections 10 and 11 are engaged with each other for sliding telescopic movement so that the loop formed by the two sections can be decreased or increased in length.

55 Extending across the loop formed by the sections 10 and 11 are the anchors or locks 14

which are formed of wire, one end of the wire being bent to provide an eye engaging over the adjacent legs of the two semi-elliptical sections and the opposite end of the 60 wire being hooked as at 15.

In the use of this device if it be desired to apply this protector to a broom, the first step is to open the hooks and then the protector is slipped over the top of the broom 65 and downward to the proper place below the stitching a of the broom. The sections of the protector are then forced toward each other, so that the loops or sections will fit snugly upon the broom and then the hooks 70 13 are forced into the broom between two of the string bands or stitching. The locking members 14 are then disposed about one-half inch inward of the legs 12, the locking members hanging down and then a key 16, 75 which consists of a loop of wire and a transverse hand-hold is inserted through the broom, the hooked end of the lock 14 is caught and pulled through the broom and hooked over the opposite portion of the 80 loop or elliptical band which embraces the broom. When this has been done the protector is securely locked in place upon the broom with the elliptical band disposed approximately halfway below the lowermost 85 line of stitching and thus the broom straws will be prevented from breakage to which they are extremely liable and the broom will be rendered stiffer than it otherwise would be. There will be less tendency therefore 90 for the broom straws to break off at the rows of stitching and the broom will last longer.

While I have illustrated a particular form 95 of my device which I have found particularly effective yet it will be obvious that the invention may be modified in many ways, without departing from the spirit of the invention, as defined in the appended claims.

I claim:—

1. A broom protector comprising an elliptical band formed in two slidably engaged sections, the sections being formed to provide hooks resiliently urged toward each 105 other and engageable through the broom straws.

2. A broom protector comprising an elliptical band formed in two slidably engaged sections, the sections carrying oppositely 110 disposed members resiliently urged to a position across each other and having later-

ally turned hooks at their free ends, the toward each other, and anchoring members hooks extending in the general direction each having an eye at one end embracing the of the length of the band, said members legs of the two sections, the opposite end 15 being adapted to be disposed through the of the anchoring member being formed with 5 straws of the broom.

3. A device of the character described comprising an elliptical band formed in two sections, the ends of each section being bent around the legs of the other section and 10 upwardly extended and having hook-shaped portions at their extremities, the upwardly extending portions being resiliently urged

Witnesses:

Jos. H. BERG,
F. W. SWIGART.

In testimony whereof I hereunto affix my signature in the presence of two witnesses.

PETER PETERSEN.
